HANGER

Allan D. Forbes, Sharon, Pa., assignor to Westinghouse Electric & Manufacturing Company, East Pittsburgh, Pa., a corporation of Pennsylvania

Application October 16, 1936, Serial No. 105,923

1 Claim. (Cl. 248—221)

This invention relates to hangers for mounting electrical apparatus.

An object of this invention is the provision of a hanger for mounting electrical apparatus on supports.

Another object of this invention is the provision of a hanger for mounting electrical apparatus having enclosing cases of different shapes on supports of different sizes and shapes.

This invention, together with other objects, will be better understood from the following description when taken in conjunction with the accompanying drawing, in which:

Figure 1 is an elevational view illustrating an assembly in which the hanger embodying the features of this invention is employed;

Fig. 2 is a top plan view of the assembly illustrated in Fig. 1;

Fig. 3 is a side elevational view of the hanger embodying the features of this invention;

Fig. 4 is a top plan view of the structure shown in Fig. 3;

Fig. 5 is a rear elevational view of the hanger shown in Fig. 3; and

Fig. 6 is a bottom plan view of the structure shown in Fig. 3.

Referring to the drawing, and particularly to Figs. 1 and 2 thereof, this invention is illustrated as comprising a hanger 10 for mounting electrical apparatus such as a distribution transformer 12 on a suitable support 14, such as a wood, concrete or metallic pole or standard. In the drawing only the case of the transformer is shown, it being understood that the case is suitable for carrying the bushings and other attachments associated with the case.

As illustrated in Figs. 3 through 6, the hanger 10 comprises an elongated channel member 16 having a face 18 and side walls 20 and 22. The ends of the face of the channel member 16 terminate in flanges 24 and 26 for receiving the transformer 12, as will be explained more fully hereinafter.

In order to seat the channel member 16 on the support 14, the side walls 20 and 22 of the channel member terminate in outwardly extending flanges 28 and 30, respectively. The flanges 28 and 30 function as feet for seating the channel member 16 on the support 14.

In order to carry the hanger 10, bolts 32 and 34 are disposed in spaced relation through the support 14. One end of each of the bolts extends outwardly from the support for receiving the hanger, as will be explained more fully herein after.

The face 18 of the channel member 16 is provided with a plurality of openings 36 and 38 in spaced relation for cooperating with the spaced bolts 32 and 34, respectively, in retaining the hanger on the support 14. The opening 36 is 5 an elongated slot, the lower end of which terminates in an enlarged opening suitable for receiving the outwardly extending end of bolt 32. The lower opening 38 is an elongated slot similar to the elongated slot portion of opening 36 and 10 terminates in an enlarged opening provided in the flange member 26 for receiving the outwardly extending end of bolt 34 as the hanger 10 is mounted on the support 14.

Since the openings 36 and 38 are in spaced 15 relation similar to bolts 32 and 34, the hanger 10 may be easily mounted on the support 14 by so seating the feet 28 and 30 of the channel member on the support that the ends of bolts 32 and 34 register with and project through the enlarged 20 portions of openings 36 and 38, respectively, in the channel member. When the openings 36 and 38 thus receive the bolts 32 and 34, respectively, the channel member may then be slipped down over the projecting ends of bolts 32 and 34 to a 25 position where the bolts are retained in the elongated slot portion of the openings 36 and 38. With the hanger 10 in this position, it may be secured to the support 14 by so tightening the bolts that the bolt heads engage the face 18 of 30 the channel member.

In order to hang the transformer 12 on the hanger, the flange 24 of the hanger 10 is provided with an opening or socket 40 for receiving a pin 42 which may be provided on the case of 35 the transformer 12. The flange 24 carries downwardly projecting side walls 6 and 8 so disposed as to seat against the face 18 of the channel member 16 to support the flange in its outwardly extending position. Other means for supporting 40 the flange may however be employed.

The pin 42 may be carried as an integral part of the case of the transformer 12. In the modification, shown in Figs. 1 and 2, the pin 42 is carried as an integral part of a flange 44 which 45 is secured to the case of the transformer near its upper edge in any suitable manner such as by welding. As shown a plurality of flanges are disposed in spaced relation about the case of the transformer. The flanges 44 in this position aid 50 in maintaining the cover of the case in position. A cover holding lug 48 is associated with each of the flanges 44 and is so positioned that one of its ends engages the cover of the transformer 12 and the other of its ends engages an associated 55

flange 44. Each of the lugs 48 is secured to an associated flange 44, by means of a bolt 50, in a position where it clamps the cover on the case. In addition to aiding in maintaining the cover in position on the case, the flanges 44 also serve as lifting hooks for lifting the transformer.

The lower flange 26 of the hanger 10 carries a bracket 52, the sides of which terminate in flanges or feet 54 and 56 for seating against the side of the transformer case. An opening 58 is provided in the bracket 52 for receiving a bolt or stud 60 which is carried on the transformer case.

When the pin 42 engages the socket 40 in the upper flange 24 of the hanger, the transformer 15 12 is supported on the hanger in the position illustrated in Fig. 1, with the feet 54 and 56 of the bracket 52 seated against the case of the transformer and the bolt 60 projecting through the opening 58 of the bracket 52. In order that the 20 transformer may be mounted on the support in a plurality of positions with respect to the support, a plurality of the bolts 60 may be disposed in spaced relation around the case similarly to the spaced flanges 44.

25 By providing the feet on the channel member and on the bracket, the hanger may be employed for mounting transformers having round, octagon or square cases on supports of different shapes. Further, by providing the spaced feet 30 on the channel member at a distance from the face thereof, it is evident that the hanger may be employed with supports of different sizes, since the opening between the spaced feet and face of the channel member is of a size sufficient to 35 receive supports of small circumferences while the feet are so spaced as to satisfactorily seat on supports of large circumferences or on supports which have substantially flat surfaces.

The hanger may be easily fabricated from a 40 single sheet of material, or in the larger types of

hangers, from suitable channel members and angle irons. The hanger member may be easily mounted on the support, as explained hereinbefore, for receiving the transformer.

Although this invention has been described 5 with reference to a particular embodiment thereof, it is not, however, to be limited thereto except insofar as is necessitated by the prior art and the scope of the appended claim.

10 I claim as my invention:

A hanger for mounting transformers on supports, the case of the transformer being provided with lifting pins and retaining bolts and the supports with spaced retaining pins, comprising, a channel member having spaced feet for 15 seating on a support, the channel member having openings disposed in spaced relation in its face for receiving the retaining pins to removably retain it on the support, a flange carried by each end of the channel member and projecting outwardly therefrom at an angle to the face of the channel member, one of the flanges having downwardly extending side walls seating against the face of the channel member for supporting the flange in its outwardly extending position, a socket 20 25 in said one of the flanges for receiving in engagement one of the lifting pins of the transformer to hang it, a bracket carried by the other of the flanges extending upwardly from the flange and being substantially parallel to the face 30 of the channel member for receiving the transformer case, spaced feet carried by the bracket for seating the case when the transformer hangs from the supported flange, the bracket having an opening therein for receiving one of the retaining 35 bolts of the case whereby the case may be locked in its supported position to prevent movement of the case to cause the disengagement of the lifting pin and socket.

ALLAN D. FORBES. 40
